THOMAS V. THOMPSON, OF BELOIT, WISCONSIN

DISK GRINDING WHEEL

Application filed April 7, 1928. Serial No. 268,158.

This invention relates to disk grinding wheels which have an abrasive disk or ring attached to the face of a disk wheel. The abrasive disk may be of any suitable abrasive material, either natural or artificial, depending on the particular work to be ground. It is customary to mold or press the abrasive material to disk form while plastic and to cement a paper or cloth back thereto. This cloth backed disk is then glued or cemented to the face of a steel wheel which in turn is adapted to be mounted on a spindle of a grinding machine for rotation at a comparatively high speed commensurate with the work to be performed. When the abrasive disk is worn down it is necessary to remove the remainder of the disk and substitute a new disk. The process of cleaning the face of the steel wheel and cementing a new disk thereto is well known in this art and it will suffice to say that these operations require careful attention and considerable time. Where disk grinders are used continuously, especially in heavy duty work, the abrasive disks wear down rapidly and must be frequently replaced because of the limited thickness of the disks. This is due to the fact that the present limits of thickness depend largely on the safety factor of the cement union between the abrasive disk and the wheel.

The primary purpose of the present invention is to improve the art of disk grinding by enabling the use of abrasive disks or rings of considerably greater thickness than is permitted by present day practice. By increasing the thickness of the abrasive disk the grinding capacity is obviously increased. Furthermore, by reason of the increased grinding capacity the disks may be used for longer periods and fewer changes are required, thus saving time and reducing the cost of grinding operations per unit.

In furtherance of the foregoing I glue, or otherwise attach to the face of a disk wheel an abrasive disk or ring of greater than ordinary thickness and provide means for peripherally clamping the disk to the wheel. This peripheral clamping means not only further secures the disk to the wheel

but it also supports and reinforces the disk so as to permit of the greater thickness and the consequent overhang. When the projecting portion of the disk is worn down substantially to the clamping means the latter will be removed or withdrawn from its normal position so as to expose the entire disk and permit full use of the disk down to the wheel. My invention contemplates, therefore, the progressive use of a relatively thick disk down to the wheel leaving no waste material other than usual with the present practice of cemented disks.

I have also aimed to provide a simple and well balanced construction having minimum diameter and weight. My invention further contemplates a construction characterized by such few parts as to not only permit of economical manufacture but to facilitate the change or adjustment after the projecting part of the disk has been worn down.

Other objects and attendant advantages will be appreciated by those skilled in this art as the invention becomes better understood by reference to the following description when considered in connection with the accompanying drawing, in which—

Figure 1 is a face view of a disk grinding wheel embodying my invention;

Fig. 2 is a section taken on the line 2—2 of Fig. 1;

Fig. 3 is an enlarged section of the rim on line 2—2 of Fig. 1; and

Fig. 4 is a detail section through the removable rim.

The disk wheel 4, usually of steel, may be suitably constructed for mounting on a spindle 5. In this case the wheel is equipped with a collar 6 adapted to be threaded onto the spindle, as shown.

The abrasive disk 7 has the usual cloth back 8 cemented thereto and is in turn cemented to the face of the wheel in the usual manner. It should be here noted that my invention contemplates the use of any abrasive disk secured to the wheel in any suitable manner. It also contemplates the use of an abrasive disk or ring of any material and any suitable shape or form. One of the principal advantages afforded, however, is the

use of an abrasive disk of greater thickness than is customary or considered safe under present day practice. For example, the drawing shows a disk approximately 18 inches in diameter and 1 5/8 inches in thickness. 5 These dimensions are, of course, merely for purpose of illustration.

In order to peripherally clamp the abrasive disk my invention contemplates in the 10 preferred embodiment the use of a clamping ring or a segment ring structure so mounted on the disk wheel that it may be removed or displaced from its normal clamping position after the projecting portion of the disk has 15 been worn down. In the present embodiment of my invention I employ a sectional ring structure comprising two ring sections or members 9 and 11 which as shown in Fig. 1 substantially circumscribes the abrasive 20 disk. These ring members are located in an annular internal groove 12 in a rim 13 which seats on the periphery and back of the disk wheel as clearly shown in Fig. 2, and is removably secured thereto by screws 14. The 25 groove 12 is so located that the ring members will be positioned over the periphery of the abrasive disk contiguous to the face of the wheel. Each ring member has an inner face 15 adapted to fit against the periphery of the abrasive disk and an outer tapered face 16 adapted to be engaged by suitable means in a wedging action for forcing the ring member inwardly and clamping it against the abrasive disk. The front and back walls 17 30 and 18 of the groove 12 are perpendicular to the axis of rotation of the disk wheel and the ring members have a sliding fit between these flat walls. The means here shown for clamping the ring members against the abrasive 35 disk is exceptionally simple and practical for the purpose, and comprises screws 19 threaded into the rim 13 from the back and provided with tapered or frusto-conical ends 40 21 the angle of which is complementary to 45 that of the taper 16. The screws 19 are spaced circumferentially about the rim so as to engage the ring members at sufficient points to exert the desired clamping pressure. This construction is exceptionally 50 rigid and permits of clamping the abrasive disk with ample pressure. Each screw is slotted or otherwise formed at its rear end for insertion of a suitable tool and when 55 tightened it will serve as a lock to secure the ring member in the clamping position. The ring members when loosened are held from shifting by locating studs 22 interposed between the split ends of said members. It 60 will be manifest that when the screws 14 and 19 are sufficiently loosened without, however, removal from the rim, the latter may be removed in its entirety from the disk wheel carrying with it the ring members 9 and 11. 65 In practice the abrasive disk or ring will be secured to the face of the disk wheel in

any suitable or preferred manner as, for example, by cementing as illustrated herein.

The clamping means will then be applied by slipping the rim over the disk wheel from the rear, then securing it in position thereon by means of the screws 14 and then clamping the ring members by means of the screws 19. The grinding wheel in this condition may be used in the manner of any disk wheel of this type until the projecting portion of 70 the abrasive disk is worn down substantially to the face of the clamping rim. The clamping rim will then be removed, thus permitting use of the remainder of the abrasive disk 75 substantially to the face of the disk 80 wheel.

It will be manifest to those skilled in this art that my invention provides for the use of an abrasive disk of considerably greater thickness and capacity than was heretofore 85 permitted with the type of disk that was cemented to the disk wheel, also that there are many practical advantages some of which are recited above. It should be further noted that my invention distinguishes from 90 the so-called "chuck" type of disk wheel in which the abrasive disk is not attached as by cementing to the wheel but is merely clamped on its periphery. In this type it is 95 necessary to remove the abrasive disk from the wheel at each setting and to insert packing plugs between the disk and wheel. Furthermore, the abrasive disk or ring can not be used to its full capacity since there always remains in the chuck a disk having a thickness of about 1 inch. My invention also distinguishes from that type known as a "metal 100 back" abrasive wheel in which the wheel has slots or grooves for reception of the abrasive material, but it is necessary to return this 105 type of wheel to the manufacturer after it has been worn down. It is possible, however, to employ in connection with my invention this latter method of attaching the abrasive 110 disk to the wheel. While this would provide 115 for greater grinding capacity it would not, however, be so desirable in respect to the method of attaching the abrasive disk to the wheel.

From the foregoing it will be seen that my 115 invention contemplates broadly the provision of means of any suitable or preferred construction for peripherally clamping an abrasive disk cemented or otherwise attached 120 to a disk wheel and for withdrawing or removing the clamping means, whereby to enable the use of abrasive disks of greater thickness and increased capacity as compared with abrasive disks cemented to disk wheels 125 under the practice prior to my invention. It will be manifest, therefore, that changes may be made in details of construction and in the form of the clamping means without, however, departing from the spirit and scope 130

of the invention as expressed in the appended claims, in which—

I claim:

1. An abrasive tool comprising a disk wheel, an abrasive disk or ring attached to the face of the wheel, a sectional clamping ring on the periphery of the disk having beveled faces, and means connecting the sectional ring to the wheel including screws having tapered ends complementary to and acting against said bevel faces adjustable for clamping the sectional ring to the disk.
2. An abrasive tool comprising a disk wheel, an abrasive disk or ring cemented or otherwise attached to the face of the wheel, a ring for peripherally clamping the disk, a wheel rim for holding the ring in position, and screws threaded in the wheel rim having tapered faces acting against the ring for applying the clamping pressure.
3. An abrasive tool comprising a disk wheel, and abrasive disk or ring secured to the face of the wheel, a ring structure for peripherally clamping the abrasive disk, a wheel rim having an annular internal groove in which the ring structure is located, the ring structure having a beveled periphery, screws threaded in the wheel rim having beveled ends engaging the beveled periphery of the ring structure for applying the clamping pressure, and means connecting the rim to the wheel permitting withdrawal of the clamping ring structure from the abrasive wheel.
4. An abrasive tool comprising a disk wheel, an abrasive disk adapted to be cemented on the face of the wheel, a rim shaped to seat on the back and periphery of the wheel and having a portion overreaching the abrasive disk, said overreaching portion having an annular internal groove, disk clamping means located in said groove, screws threaded in the rim and connected with the clamping means for exerting the clamping pressure, and means connecting the rim to the wheel.
5. An abrasive tool as set forth in claim 9, in which the rim is bodily movable upon and with respect to the wheel for withdrawing the clamping means from the abrasive disk to permit the use of the remaining portion of the disk.
6. An abrasive tool comprising a disk wheel, an abrasive disk adapted to be positioned on the face of the wheel, a rim shaped to seat on the back and periphery of the wheel and having a portion overreaching the abrasive disk, said portion having an annular internal groove, a sectional clamping ring disposed in said groove tapered on its periphery, screws threaded in the rim from the back thereof having tapered forward ends complementary to and acting against the tapered periphery of the clamping ring for exerting the clamping

pressure, and means fastening the rim to the wheel, the rim being movable rearwardly on the wheel to withdraw the clamping ring from the abrasive disk.

In witness of the foregoing I affix my signature.

CERTIFICATE OF CORRECTION.

Patent No. 1,767,821.

Granted June 24, 1930, to

THOMAS V. THOMPSON.

It is hereby certified that error appears in the printed specification of the above numbered patent requiring correction as follows: Page 3, line 47, claim 5, for "claim 9" read "claim 4"; and that the said Letters Patent should be read with this correction therein that the same may conform to the record of the case in the Patent Office.

Signed and sealed this 22nd day of July, A. D. 1930.
